(No Model.)

J. TITTLE.
WATER BACK FOR FURNACES.

No. 495,072.

Patented Apr. 11, 1893.

Fig. 1.

UNITED STATES PATENT OFFICE.

JAMES TITTLE, OF JOHNSTOWN, PENNSYLVANIA.

WATER-BACK FOR FURNACES.

SPECIFICATION forming part of Letters Patent No. 495,072, dated April 11, 1893.

Application filed January 19, 1893. Serial No. 458,908. (No model.)

To all whom it may concern.

Be it known that I, JAMES TITTLE, a citizen of the United States, residing at Johnstown, in the county of Cambria and State of Pennsylvania, have invented certain new and useful Improvements in Water-Backs for Furnaces; and I do declare the following to be a full, clear, and exact description of the invention, such as will enable others skilled in the art to which it appertains to make and use the same, reference being had to the accompanying drawings, and to the letters of reference marked thereon, which form a part of this specification.

The invention relates to waterbacks for boilers or furnaces, the same being water as well as steam tight and thus liable to explode when the water has been shut off therefrom by any cause whatever.

The object of my invention is to so construct and arrange a waterback that all liability to explosion will be removed in any contingency.

Figure 1 of the drawings is a horizontal section, and Fig. 2 a vertical cross section.

In the drawings, A represents the brickwork of a furnace and B the waterback arranged to run horizontally around the sides and rear of the firebox C. It is made open at the top and extends through the front so as to have the projecting ends b c, of which the end b communicates with the inlet supply pipe D and the end c with the outlet pipe E which may lead to a suitable reservoir for hot water. These pipes D E are provided with the stop-cocks d e which are placed at such point as may be most convenient for use. The desired degree of temperature at which the waterback shall supply the water to the reservoir, may

be very accurately adjusted, by manipulating the cocks d e. By closing the outlet cock e 40 more, the water flows more slowly through the waterback and becomes warmer before going to the reservoir.

The waterback may be made of wrought or cast metal with the upper side open for its 45 whole length, and the firebox of brick in the usual way, the inner side of the waterback facing the open space of the waterbox, while the top-open ends project beyond the furnace. There is a continuous flow of cold water into 50 the waterback from the inlet pipe, and of warm water out at the outlet pipe; thence to a reservoir, from which the hot water may be pumped to the boiler at such temperature as may be desired. This purifies the water 55 and prepares it for conversion into steam. If from any cause, the water should cease to flow into my waterback, an avenue is provided for the escape of steam without an explosion.

What I claim as new, and desire to protect by Letters Patent, is—

A furnace waterback which is arranged horizontally about the inside of firebox, made open at top to prevent explosion when the water supply ceases, and having the ends b c extended through the front of firebox; the said ends being provided with cocks d e, whereby the degree of heat imparted to the water may be regulated as set forth.

In testimony whereof I affix my signature in presence of two witnesses.

JAMES TITTLE.
